UNITED STATES PATENT OFFICE

WILLIAM F. HENDRY, OF OSSINING, NEW YORK, ASSIGNOR, BY MESNE ASSIGNMENTS, TO MANHATTAN ELECTRICAL SUPPLY COMPANY, INC., OF JERSEY CITY, NEW JERSEY, A CORPORATION OF NEW JERSEY

ELECTRODE STRUCTURE FOR ELECTRICAL DISCHARGE TUBES

Application filed December 30, 1927. Serial No. 243,653.

This invention relates to electrode structures for electrical discharge tubes and pertains more particularly to electrodes of the general type disclosed in my Patent No. 1,628,045 and copending application Serial No. 180,788, filed April 4, 1927.

In the above mentioned application is disclosed an improved form of electrode structure for an electrical discharge tube of the illuminating type. This electrode structure which consists of a point electrode surrounded by a sleeve of insulating material spaced a slight distance therefrom, has been found to be very satisfactory in most respects. However, it is necessary carefully to degasify the entire electrode assembly before putting it into use in a discharge tube. As there is quite a large amount of insulating material in the assembly and this insulating material contains a large quantity of absorbed gases, degasification is accomplished only after a relatively long treatment. Furthermore, in order to obtain the accurate dimensions desirable for the parts used in the making of such electrode structures it is necessary, for best results, to use special insulating material which can be reduced to accurate dimensions.

It is an object of my invention in order to avoid the use of large amounts of insulating material, to provide an improved electrode structure wherein a specially constructed metal sleeve is used in place of the insulating sleeves disclosed in the above mentioned application and patent. In accordance with my present invention, I hold this sleeve in its proper position by insulating means which may be in the form of small blocks of any desirable insulating material, such as porcelain or Lavite, moulded or otherwise fashioned to the desired shape. This construction reduces the amount of insulating material to a minimum and hence reduces the length of time necessary for the degasification of the electrode structure, while at the same time providing a structure readily adaptable to mass production in a cheap and easy manner.

In order that the invention may be fully understood I have illustrated in the accom-

panying drawings, and described herein-after, a preferred embodiment thereof.

In the drawings, Fig. 1 illustrates an electrical discharge tube having positioned therein an electrode structure constructed in accordance with my invention.

Fig. 2 illustrates a modified form of electrical discharge tube having a similar electrode structure therein.

Fig. 3 is a view taken along section lines 3—3 of Fig. 2.

Fig. 4 shows in perspective one of the block insulators used in the electrode structure.

Reference numeral 1 indicates an electrode which may be of any desired conducting material such as aluminum, copper, carbon or the like having a rod like extension or base 8 and surrounded by a metallic sleeve of conducting material 2. This metallic sleeve has an extension tube 5 which is divided longitudinally by means of slits 16 into a plurality of segments 17, each having therein an opening 6 for receiving an insulating block 7. The block 7 may be constructed of any desired insulating material such as porcelain, 70 Lavite or similar material, molded or otherwise fashioned to the desired shape. The insulating blocks bear against rod-like extension 8 of electrode 1. The blocks are pressed firmly against the rod 8 by the segments 17 80 of extension tube 5 of sleeve 2 which extension is made of sufficiently resilient material to insure proper alignment, through the agency of the insulating plugs, relative to the rod 8. With this arrangement it is very easy 85 to slide the sleeve relative to the rod and active portion to secure the proper positioning thereof.

Placed around the sleeve 2, for preventing any discharge from flashing back around the lead-in wire of the electrode, and for centering the electrode structure in the discharge tube, is a flange 4 which has a shoulder 3 for holding the flange in position around the sleeve. In order to prevent longitudinal displacement of the flange 4 with respect to the sleeve 2, the shoulder 3 of flange 4, and the sleeve 2 are fastened together in some suitable manner, such as by deformation 9. As disclosed in my aforementioned patent the sleeve 100

is to be spaced but a slight distance from the active portion of electrode 1 and the sleeve would therefore have to be carefully aligned with respect to the said active portion. This alignment, in the present structure is assured by the insulating blocks 7 which are made long enough to give a good bearing.

The entire electrode assembly is positioned within one end of a discharge tube 10 and is held in its proper position by a deformation 11 in the wall of the tube, with which the flange 4 of the sleeve 2 contacts. The electrode structure is prevented from movement in a backward direction by means of a tubular extension 12 which forms an inwardly turned portion of the envelope of the tube and which surrounds the back end of the rod 8, the inner end of the tube 12 contacting with the ends of insulating blocks 7. The construction of the insulating blocks is disclosed more in detail in Fig. 4 wherein it will be noted that the blocks consist of an elongated portion 13 having an upwardly projecting shoulder 14 which passes through one of the openings 6 in the tube 5, the inner face 15 of the elongated portion 13 being curved to conform to the curvature of the rod 8.

The electrode structure illustrated in Fig. 2 is exactly the same as that shown in Fig. 1, it being positioned within a tube 18 in slightly different manner than in the tube 10. In the tube of this figure the electrode structure is held in its proper position by a lead-in wire 19 which serves to hold the flange 4 of the sleeve 2 against a packing of glass wool 20 which in turn bears against shoulder 21 of the tube 18. As set forth in my above mentioned application, the glass wool serves to conduct heat from the electrode structure and thus insure the more efficient operation of the tube.

While I have illustrated the sleeve 2 and flange 4 as being separate pieces, it will be understood that they might likewise be made of a single unitary piece, or the sleeve and flange might be made unitary and fashioned to form a telescope joint with the extension tube 5. The sleeve 2 might, if desirable, be used alone without the flange 4. Instead of having three insulating blocks as shown, a different number might be used, and while it is preferable to use blocks having shoulders projecting through openings cut in the extension 5 of the sleeve 2, other constructions might be used, for example, a split cylinder of insulating material might be placed inside of the extension tube 5. I prefer to construct the sleeve and flange of sheet material, by punching, for example, but in some cases it might be found advantageous, for structural reasons, to utilize a sleeve of heavy material, die cast or machined to the correct dimensions. In such a case, the extension tube 5 might be made a separate piece and be telescoped with the sleeve for a portion of its length.

I have described a particular embodiment of my invention merely for the purpose of illustration, and do not intend to be limited thereby as it is to be understood that various modifications and adaptations of the invention, such as would occur to one skilled in the art, may be made without a departure from the spirit of the invention as set forth in the following claims.

What I claim is:

1. In an electrode structure for an electrical discharge device, an electrode having an active portion and a base portion, and a sleeve of conducting material surrounding said active portion and separated a slight distance therefrom to provide a free space, said sleeve being spaced from said base portion by a plurality of radially disposed block like insulating means placed between the said base portion and the inside of said sleeve. 75

2. In an electrode structure for an electrical discharge device, an electrode having an active portion, a base portion, and a metallic sleeve surrounding said active portion at a slight distance therefrom, said sleeve being cut to provide segments, said segments having openings therein, and insulating means cooperating with said segments and openings for holding said sleeve in its proper position. 90

3. In an electrode structure for an electrical discharge device, an electrode structure comprising an electrode, a metallic sleeve surrounding said electrode at a slight distance therefrom, said sleeve having cuts at one end dividing said sleeve into segments, and insulating means positioned between said sleeve and said electrode in such fashion as to be resiliently gripped by said segments and to hold said sleeve in its proper alignment. 95

4. An electrode structure for an electrical discharge tube comprising an electrode, and a sleeve having resilient segments, said sleeve surrounding said electrode and being spaced and held in alignment by means of insulators placed between said segments and 100 said electrode.

5. In an electrode structure for an electrical discharge device, an electrode having an active portion, a base portion and a metallic sleeve surrounding said active portion at a slight distance therefrom, said sleeve being cut to provide segments, and insulating means cooperating with said segments for holding said sleeve in its proper position. 115

6. An electrode structure as set forth in claim 5, wherein means is provided for preventing displacement of the said insulating means relative to the said sleeve. 120

7. In an electrode structure for an electrical discharge device, an electrode having an active portion and a base portion, and a sleeve of conducting material surrounding said active portion and separated a slight distance therefrom to provide a free space, said materially conductive sleeve being electrically 125

unbiased with respect to said electrode and spaced from the base portion thereof by means of a plurality of spaced insulators.

5 In testimony whereof, I have signed my name to this specification this 28 day of December 1927.

WILLIAM F. HENDRY.
